UNITED STATES PATENT OFFICE.

JOSEPH MIDDLEBY, OF BOSTON, MASSACHUSETTS.

BAKE-OVEN.

SPECIFICATION forming part of Letters Patent No. 522,075, dated June 26, 1894.

Application filed January 26, 1893. Serial No. 459,872. (No model.)

To all whom it may concern:

Be it known that I, JOSEPH MIDDLEBY, of Boston, in the county of Suffolk and State of Massachusetts, have invented certain new and useful Improvements in Bake-Ovens, of which the following is a specification.

This invention relates to an improvement in bake-ovens, the object being to provide a commodious double oven, throughout which the heat will be equally distributed; to provide a construction whereby the parts may be readily fitted together; to make provision for hearth-baking, and to provide for readily gaining access to the flues, for the purpose of cleaning or removing them.

Of the accompanying drawings, forming part of this specification: Figure 1 shows a perspective view of the oven. Fig. 2 represents the oven as bisected, making two sectional views in perspective, one looking toward the front of the oven, and the other looking toward the rear. Fig. 3 shows a longitudinal section. Fig. 4 shows a fragmentary horizontal section, on line 4—4 of Fig. 3. Fig. 5 shows a detail perspective of castings which form a union, connecting the flues of the oven. Fig. 6 shows a section on line 6—6 of Fig. 3.

The same letters of reference indicate the same parts in all the figures.

In the drawings: The reference letter *a* designates the outside casing of the oven, which is made of sheet metal, and supported on four legs *b*, braced by straps *c*, which are bolted to the legs and to a flange *d* on the said outside casing. Within the casing is a lining *e*, also of sheet metal, and a filling of asbestos *f* is interposed between the said lining and the outside casing, leaving a dead air-space *f'* all around. An ash-pit *g* stands on the floor below the front part of the oven, and a fire-pot *g'* is supported on this ash-pit, suitable grate-bars *g''* being provided in the bottom of the fire-pot. A horizontal plate *h* is supported above the fire-pot, and has an opening over the latter; a transverse deflector-plate *h'* is fastened on the upper surface of the said horizontal plate *h*, by means of ears *h''* formed on said transverse deflector-plate and bolts *h'''* extending through said ears. A hearth *i*, composed of tiles, is supported above the horizontal plate *h*, and rests on the trans-

verse plate *h'* which serves to support its rear end.

Horizontal flues *j* extend along the bottom of the oven, their forward ends fitting over flanges *j'* formed on the rear side of a casting *j''*, which fits against the back of the hearth *i*. The horizontal flues *j* are made in sections, to facilitate their ready removal, and the sections are united by means of fluted straps *k* above and below them. These straps are connected at one side, by means of an opening in one, which is engaged by a lip *k'* on the other, thus forming a hinge. These straps engage the surfaces of all the flue-sections, and abut between the flues. Their ends opposite the hinge are connected by means of a pin *k''*. It will be seen that, by removing this pin, the upper fluted strap may be raised on the hinge, and any one of the flue-sections then easily removed. Cement will be inserted between the ends of the flue-sections to form a tight joint.

The horizontal flues *j* connect with a union fitting in the lower rear corner of the oven, said union consisting of a casting having the form of a rectangular box, bisected longitudinally. This casting thus consists of two parts *l l'*, the front one *l'* of which has a series of oval flanges *l''* to receive the ends of the horizontal flues *j*, and a series of semi-oval flanges *l'''* on the upper side. The rear part *l* of the casting has a similar series of semi-oval flanges *l''* on the upper side, and the two portions *l* and *l'* are fitted together and secured by bolts *l''*; and, when thus secured together, the semi-oval flanges on the upper sides of the two parts of the casting fit together and receive the lower ends of a series of vertical flues *m*, whose upper ends fit over flanges *m'* of an upper casting *n* of the same construction as the casting *l l'*, only reversed. A series of horizontal flues *n''* have their rear ends fitting over flanges *n'* of the casting *n*, and their forward ends connect with a union located at the front part of the oven, and composed of two sections *o*, having the form of the section *l'* of the union casting already described. These two sections *o* are bolted together, so as to form a three-way union, one branch of which fits through the front of the oven and is closed by a removable plate *p*, fastened by

screws p' to the front of the oven. There are two of these plates p , and they close the front ends of all the flues n^2 ; hence it will be seen that, by removing said plates, access may be gained to the flues, for the purpose of cleaning the same.

A series of vertical flues q is connected to the upwardly-extending branches on the union o , and their upper ends fit over flanges of a casting r , secured to the top of the oven. A box s is fastened above the top of the oven, and all the vertical flues q communicate through the casting r with said box, on which a stack t is mounted, to carry off the products of combustion.

Gratings $u u'$ are supported above the horizontal flues j and n^2 , and the matter to be baked in the oven will be placed on these gratings.

The tendency of the heated air to rise may create too great a heat in the top of the oven, and, to overcome this, a perforated off-take flue v extends along the top of the oven, and communicates, through an elbow v' with the stack t . The end of the flue v is open at about the middle of the oven; and, by opening a damper v^2 in the flue, the heated air which has risen to the top of the oven, may be conducted out into the stack t .

The products of combustion rising from the fire-pot g' first strike the hearth i , and, as this hearth is composed of tiles, as previously explained, there is no danger of its burning out. The products of combustion are deflected laterally by the transverse plate h' , and are thereby distributed equally to the set of horizontal flues j , and pass through the same, and then up the vertical flues m at the back of the oven, and then into the flues n^2 , by which they are conducted to the front of the oven, where they pass into the vertical flues q , by which they are conducted to the stack t . By this arrangement of flues and manner of conducting the products of combustion, the oven will be uniformly heated throughout, so that matter on the gratings u and u' will be equally baked.

Hearth-baking may be accomplished on the tiles i , such as the baking of Dutch bread and the like.

Suitable doors y are provided on one side of the oven, by which to gain access to both the upper and lower parts of the oven. Doors z and x are also provided at the front of the ash-pit and fire-pot.

Having thus described my invention, what I claim as new, and desire to secure by Letters Patent, is—

1. In a bake-oven, the combination of a fire-pot; a horizontal plate above the same; a transverse deflector-plate on the said horizontal plate; a hearth resting on said deflector-plate; and flues, whose ends open in front of the deflector-plate in the manner described.

2. In a bake-oven, the combination of a set

of flues composed of sections; and fluted straps uniting said sections and connected at one end by a hinge and at the other by a detachable fastening.

3. In a bake-oven, the combination of two sets of horizontal flues; vertical flues connecting the same; vertical flues leading to the stack; and unions uniting the flues and composed of castings of two patterns, one of rectangular box-like form having oval flanges on one side to receive the flue-ends and a series of semi-oval flanges on a side at right angles to said first-named side, and the other pattern being of a rectangular box-like form with semi-oval flanges on one side; substantially as described.

4. In a bake-oven, the combination of a set of horizontal flues, whose ends open out of the front of the oven; and a plate or plates closing the said flues and detachably secured to the front of the oven.

5. In a bake-oven, the combination of a fire-pot at the front of the oven; a hearth above said fire-pot; a set of separate horizontal flues extending along the bottom of the oven and having their front ends opening below said hearth; a set of separate vertical flues extending along the back of the oven and communicating with the said horizontal flues; a second set of separate horizontal flues communicating with the vertical flues and extending to the front of the oven; a set of separate vertical flues communicating with the front ends of said second set of horizontal flues; a box on the top of the oven and communicating with said last-named set of vertical flues; and a stack on said box.

6. In a bake-oven, the combination of a fire-pot at the front of the oven; a hearth above said fire-pot; a set of separate horizontal flues extending along the bottom of the oven and having their front ends opening below said hearth; a set of separate vertical flues extending along the back of the oven and communicating with the said horizontal flues; a second set of separate horizontal flues communicating with the vertical flues and extending to the front of the oven; a set of separate vertical flues communicating with the front ends of said second set of horizontal flues; a box on the top of the oven and communicating with said last-named set of vertical flues; a stack on said box; and an off-take flue, leading from the top part of the oven into the said stack and provided with a damper, for the purpose described.

In testimony whereof I have signed my name to this specification, in the presence of two subscribing witnesses, this 17th day of January, A. D. 1893.

JOSEPH MIDDLEBY.
